(57) **CLAIM**

The ornamental design for a drape-over article with storage, as shown and described.

DESCRIPTION

FIG. 1 is a top-front perspective view of a drape-over article with storage showing our new design in an in-use configuration, viewed from the right side;

FIG. 2 is a top-rear perspective view thereof, viewed from the right side;

FIG. 3 is a bottom-front perspective view thereof, viewed from the left side;

FIG. 4 is another bottom-front perspective view thereof, viewed from the right side;

FIG. 5 is a front elevation thereof;

FIG. 6 is a rear elevation thereof;

FIG. 7 is a top plan view thereof;

FIG. 8 is a bottom plan view thereof;

FIG. 9 is a left side elevation thereof;

FIG. 10 is a right side elevation thereof;

FIG. 11 is another top-front perspective view thereof, viewed from the right side, and shown in a lowered in-use configuration;

FIG. 12 is another top-front perspective view thereof, viewed from the right side, and shown in a non-use configuration; and,

FIG. 13 is another top-front perspective view thereof, viewed from the right side, and shown with articles positioned therein.

The broken lines in FIG. 13 showing a book and an electronic device and accessory depict environmental subject matter that form no part of the claimed design. The remaining broken lines depict portions of the drape-over article with storage that form no part of the claimed design.
